DATA CONVERSION OPERATION
BOYERS, PA

Josiah Pratt Junr.
Seths Patent.

The schedule referred to in these Seths Patent and making part of the same containing a description in the words of the said Josiah Pratt Junr. himself of his improvement in the Machine for making type.

To all to whom these presents shall come. We it known that Josiah Pratt Junr of Whittemore in the County of Franklin and State of Massa-
chussets have invented a new and useful Machine for Making type and
that the following is a full and exact description of the construction
and operation of the said Machine as invented by me. To the two
cast steel dies designated by the appellation of hammer die and anvil
die. The hammer die should be six inches in length about three inches
wide and three high. The sides and ends of both dies should be
perfectly straight. The anvil die should be of the same dimensions
as the hammer die, though it may be an eighth of an inch wider.
The face of the anvil die, meaning by the face of the dies that portion
of the surface of the dies contained between the length and width of
the dies, should be made a regular convex curve whose perpendicular
would bear eighth of an inch more or less. One and a quarter of an
inch of the face of the hammer die from the front end should be regular-
ly rounded, and most rounded at the very end. The remainder of the
face of the hammer die after one and a quarter of an inch from the front
end, should be a regular concave, the right-hand side of the face more
concave than the left-hand side, so that there should be a space of three-
eighths of an inch on the right-hand side and one eighth of an inch
on the left-hand side in the centre of the face, when applied to the
face of the anvil die, as represented in the model. It is intended that
the two faces of the dies shall not touch each other when brought in con-
tact except at the point one and a quarter inch from the front end
of the hammer die and at the rear ends of both dies. In using the
dies in the operation of hammering, the hammer die should be so placed

that its face should project to the right of the anvil die one quarter or five sixteenths of an inch leaving one quarter or five sixteenths of an inch of the face of the anvil die to the left. The dies are used in the same manner and on the same principle of the common trip hammer propelled by water power. With the aforementioned dies placed and used in manner aforesaid we lay the foundation of the age from the bar of iron. To finish the age there is another set of dies described as follows to wit, take two cast steel dies each of about eight inches long three inches wide on the face and three high, sides and ends straight or other wise like the former ones. The faces of these two last dies are to be made precisely alike as follows. From the centre of the faces of the dies make them concave each way two and five eighths of an inch or about that so that when the faces of these dies are applied to each other, the space between the dies in front shall be three quarters of an inch in the centre and the space between the dies in the rear shall be one eighth or one sixteenth of an inch. From the extremities of the cavities the remainder of the faces on each end of the dies must be gradually rounded and most rounded at each of the ends so that the space between the extreme ends shall be about one half of an inch when the faces are brought in contact as represented by the model, forming at the ends of the dies pins for the purpose of welding and spreading the age. In using these last dies in the manner and on the principle aforesaid they are so placed as not to project. The faces of the last mentioned dies when applied to each other will touch each other ^{only} at the points where the concavities end. in. The manner of holding the iron under the dies and the skill of moulding, the age can be learned only by observation and practice
